UNITED STATES PATENT OFFICE.

FRANK FRANCE, OF CHICAGO, ILLINOIS.

WELL-DRILL.

1,022,472.

Specification of Letters Patent.

Patented Apr. 9, 1912.

Application filed August 8, 1910. Serial No. 576,109.

To all whom it may concern:

Be it known that I, FRANK FRANCE, citizen of the United States, residing at Chicago, in the county of Cook and State of Illinois, have invented certain new and useful Improvements in Well-Drills, of which the following is a specification.

This invention relates to improvements in drills and particularly to well drills, and 10 has for its object to provide a drill of this kind that is novel in construction, simple and easy in its operation and very efficient in its work.

One of the main objects of the invention 15 is to provide a drill that will also act as a conveyer and will take out water as well as earth.

With these and other objects in view, which will be more fully described in the 20 following specification, I have constructed a drill of the character described, which is illustrated in the accompanying drawings in which,

Figure 1 is an elevational view of a drill 25 and operating means shown partly in section, Fig. 2 is a top plan view of a collar, Fig. 3 is a sectional view taken on the line A—A Fig. 1 looking down, Fig. 4 is a vertical section of the lower part of the drill, and Fig. 30 5 is a side elevation of the drill showing one section partially removed.

Like reference characters indicate like parts throughout the several views of the drawing and in the specification, in which—

35 1 indicates a cylinder having a removable section 2 which is held in position by a member 13 having a portion of its upper edge recessed to receive the lower end thereof and a collar 5, having a channel 6 therein, which 40 is adapted to engage the pin 7 on the neck 8 so as to permit the collar to slide down over the reduced part 9 of the section 2 after which it is given a slight turn thereby being locked against vertical movement.

45 In the bottom part of the cylinder 1 is a ring 10 to which are hinged two doors 11 and 12 which close of their own weight but which will be forced open by incoming earth or water. To the ring 10 is secured a member 13 having a cutting edge 14 on the bottom thereof. To the upper part of the cylinder is fastened a bifurcated supporting member 15 which terminates in a neck 8, having a reduced screw threaded upper portion 16.

A connecting member 17 having an en-

larged end 18 with a screw threaded portion 19 in the bottom thereof for engagement with the screw threaded member 16, has an enlarged upper end 20. The enlarged 60 end 18 has a bearing 21 which acts as a stop for the drawing member which consists of the tube 22 which has a hollow plug 23 screw threaded to its lower end, through which passes the connecting rod 17. The 65 tubular member 22 is provided with slots 24 at one or more places thereon, so as to permit of the outflow of any water that gets into the tube.

The object of the removable section 2 is 70 to permit of entirely closing the cylinder in case water or slush is being taken from the bore.

Where clay or sandy soil is being removed the section 2 is not used, it not being necessary as the soil will pack in the cylindrical member and be held therein by the curved walls thereof and the device can be more easily emptied.

Having fully described my invention, I 80 claim and desire to secure by Letters Patent:

1. A well drill consisting of a cylindrical member having a longitudinal section removable therefrom, and a cutting member 85 on the bottom thereof, said cutting member being removable, a locking member, the upper portion of said cylindrical member and removable section being reduced to receive said locking member.

2. A well drill consisting of a cylindrical member having a longitudinal section removable therefrom, and a cutting member on the bottom thereof, said cutting member being removable, a locking member, the 95 upper portion of said cylindrical member and removable section being reduced to receive said locking member, said locking member consisting of a collar.

3. A well drill consisting of a cylindrical member having a longitudinal section removable therefrom, a cutting member on the bottom thereof, said cutting member being removable, a locking member, the upper portion of said cylindrical member and removable section being reduced to receive said locking member, said locking member consisting of a collar, and means for fixing said collar in engagement with said cylindrical member and removable section.

4. A well drill consisting of a cylindrical member having a longitudinal section re-

movable therefrom, a cutting member on the bottom thereof, said cutting member being removable, a locking member, the upper portion of said cylindrical member and removable section being reduced to receive said locking member, said locking member consisting of a collar, means for fixing said collar in engagement with said cylindrical

member and removable section, and closures for the bottom of said cylindrical member. 10

In testimony whereof I affix my signature, in presence of two witnesses.

FRANK FRANCE.
